UNITED STATES PATENT OFFICE.

SALVADOR RUBIO, OF LOS ANGELES, CALIFORNIA.

FULCRUM DEVICE FOR EARTH-WORKING IMPLEMENTS.

Application filed April 28, 1924. Serial No. 709,626.

To all whom it may concern:

Be it known that I, SALVADOR RUBIO, a citizen of Guatemala, and a resident of Los

Angeles, in the county of Los Angeles and State of California, have invented certain new and useful Improvements in Fulcrum Devices for Earth-Working Implements, of which the following is a specification.

My invention relates to earth working implements such as shovels, forks, hoes and the like, and a purpose of my invention is the provision of a device adapted to be attached to the leg and providing a fulcrum upon which the handle shank of an earth working implement can be manually rocked to permit lifting of a quantity of earth with less labor than heretofore required and to accomplish more work with greater ease.

15 I will describe only one form of fulcrum device embodying my invention, and will point out the novel features thereof in claims.

In the accompanying drawings

20 Figure 1 is a view showing one form of fulcrum device embodying my invention in applied position with respect to the leg;

Figure 2 is a sectional view taken on the line 2—2 of Figure 1;

25 Figure 3 is a fragmentary sectional view taken on the line 3—3 of Figure 1.

Referring specifically to the drawings, in which similar reference characters refer to similar parts, my invention in its present embodiment comprises a flexible supporting member 15, preferably formed of a relatively heavy sheet of leather which is bent in the form of a U, so as to accommodate the leg, and which is curved inwardly or rearwardly so as to conform generally to the leg

30 at a point directly above the knee joint. This supporting member 15 is sufficiently long to extend both above and below the knee joint and is adapted to be secured in position upon the leg by means of a strap

35 16 split at its lower end to provide a plurality of tabs 17 which are riveted or otherwise secured to the upper end of the member 15. The upper end of the strap 16 is looped and provided with a buckle 18, by means of

40 which the strap can be secured to the usual trousers supporting belt 19 of the person wearing the device. A second strap 20 is adapted to encircle the leg above the knee and this strap is adjustable vertically upon

45 the strap 16 by virtue of a strip 21 riveted

to the strap 20 and between which the strap 16 slidably fits, as clearly illustrated in Figure 3.

The supporting member 15 provides means for rigidly supporting upon the leg 60 an element designated generally as E, such element in the present instance being formed of a single length of rigid material, preferably metal, which is bent into substantially semi-circular form, and provided at its ends with eyes 22 engaged by looped ends of an adjustable strap 23 which is adapted to embrace the leg adjacent the knee joint, as clearly illustrated in Figure 1. To prevent

longitudinal as well as vertical displacement of the element E, strap loops 24 are riveted to the member 15 so as to embrace the element adjacent the eyes 22. To prevent longitudinal or circumferential displacement of the element a relatively large 70 strap loop 25 is riveted to the member 15 at a point between the strap loops 24. This

strap loop 25 is formed from a single length of leather or other flexible material which is folded upon itself to provide between its 75 ends sleeves 26 which are spaced to accommodate a projection or bar 27 formed on the element E. This projection or bar 27 is formed by bending the single length of metal or other material from which

the element is formed at a point between its ends and upon itself. The projection or part 27 is thus constructed of two stretches of metal having twice the strength 80 of the semi-circular portion of the element 85 E. Further, the free end of the projection or bar 27 is bent upwardly to provide a lip 28 which functions to confine the handle shank of an earth working implement against lateral displacement from the bar. 90

In practice, the device is applied to the leg in the manner illustrated in Figure 1, with the strap 16 connected to the belt 19 to determine the elevation of the device upon the leg, while the strap 20 embraces the leg to prevent forward displacement of the device from the leg. The strap 23 embraces the leg directly below the knee joint so as

100 to maintain the member 15 in snug engagement with the leg. By means of these straps the member 15 is fixedly secured upon the leg so as to cause the element E to occupy a definite position at all times. With the device applied, the bar 27 projects inwardly

105 from the leg at a point adjacent to the knee 110

- joint so that the handle shank of an earth working implement, such as a shovel, can be placed upon the bar in the manner indicated in dot and dash lines in Figure 1.
- 5 With the shovel so applied, it will be clear that it is free for forward movement to load the shovel, whereupon, by gripping and forcing the handle downwardly, the handle shank will rock about the bar 27 as a center, 10 thus elevating the shovel and its load to convenient position for dumping.

By actual experiment it has been found that by employing a fulcrum device of the character just described the operation of a 15 shovel or other earth working implement is greatly facilitated, the bar 27 providing a fixed point upon which the shovel can be rocked to effect with ease the initial lifting of the shovel and its load.

- 20 Although I have herein shown and described only one form of fulcrum device for earth working implements embodying my invention, it is to be understood that various changes and modifications may be 25 made herein without departing from the spirit of the invention and the spirit and scope of the appended claims.

What I claim is:

1. In combination, an earth working implement, a rigid element providing a fulcrum point about which a shovel may be rocked, and means for detachably securing the element in a definite position with respect to the knee.
- 30 2. A fulcrum device of the character described comprising a supporting member, means for securing the supporting member in fixed position upon the leg, and an element secured to the supporting member to 40 provide a support for the shank of an earth working implement upon which the latter can be rocked for the purpose described.
- 45 3. A fulcrum device of the character described comprising a flexible supporting member, means for securing the member in fixed position upon the leg, and an element secured to the supporting member and projecting laterally therefrom for the purpose described.
- 50 4. A fulcrum device of the character described, comprising a supporting member adapted to be secured to the leg to occupy a definite position with respect to the knee, and an element rigidly secured on the member and providing a support for the handle

shank of an earth working implement upon which the latter can be rocked.

5. A fulcrum device of the character described comprising a supporting member adapted to be secured to the leg in definite position with respect to the knee, and an element rigidly secured on the member and providing a support for the handle shank of an earth working implement upon which the latter can be moved longitudinally and 65 rocked, for the purpose described.

6. A fulcrum device of the character described comprising a supporting member adapted to be secured to the leg in definite position with respect to the knee, and an element rigidly secured on the member and providing a support for the handle shank of an earth working implement upon which the latter can be rocked, and a projection on the 70 element for confining the handle shank on the element against lateral displacement.

7. A fulcrum device of the character described comprising a sheet of flexible material, an element formed of rigid material secured to said sheet and curved to maintain the sheet in substantially U-form, a bar 80 extending from the element, and means associated with the element and sheet for detachably securing the sheet to the leg.

8. A fulcrum device of the character described comprising a sheet of flexible material, an element formed of rigid material secured to said sheet and curved to maintain the sheet in substantially U-form, a bar 90 extending from the element, means associated with the element and sheet for detachably securing the sheet to the leg, and a lip formed on the bar for the purpose described.

9. A fulcrum device of the character described comprising a sheet of flexible material, an element secured to the material, said element being formed of rigid material and curved to maintain the sheet in curved form, a strap secured to the upper end of the sheet and having an adjustable loop 100 adapted to engage a belt, a second strap adapted to encircle the leg above the knee and adjustable vertically on the first strap, a third strap secured to the element and adapted to partly embrace the leg below the knee, a bar extending from the element and forming an integral part thereof, and a lip 105 formed on the bar.

SALVADOR RUBIO.
